UNITED STATES PATENT OFFICE.

CLAYTON T. COOK AND CHARLES B. COOK, OF OWOSSO, MICHIGAN.

ACETYLENE-GAS GENERATOR.

1,353,455.

Specification of Letters Patent. Patented Sept. 21, 1920.

Application filed August 8, 1916. Serial No. 113,739.

To all whom it may concern:

Be it known that we, CLAYTON T. Cook and CHARLES B. Cook, citizens of the United States, residing at Owosso, in the county of Shiawassee and State of Michigan, have invented certain new and useful Improvements in Acetylene-Gas Generators, of which the following is a specification.

Our invention relates to acetylene gas generators of the displacement type in which the increase of gas pressure tends to lift the carbide holder from the water and thereby automatically control the generation of gas in proportion to the amount consumed.

One of the objects of our invention is to provide a generator which will not only automatically generate the gas in accordance to the consumption but will also accurately regulate the pressure of gas in the supply pipe or gas main so that the pressure or flow at the burner will be uniform. A further object is to greatly simplify the construction of the generating apparatus.

In the accompanying drawings Figure 1, is a vertical section of an acetylene generator embodying our invention; Fig. 2, is a cross-section on the line 2—2 of Fig. 1; and Figs. 3 to 6 inclusive are enlarged detail views of certain parts hereinafter described.

The outer tank or well 1, is preferably of cement and may be conveniently embedded below the level of the ground. The inverted gas bell 2, has its lower portion extending into the water 3 in the tank and rises and falls in accordance with the variations in the volume of gas, being guided on the rods 5, secured to the sides and bottom of the tank, by the guide-members 6, secured to the bell.

The dip carbide-container or receptacle 8, is formed with a conical bottom provided with perforations 9, which admit water to the carbide 10, as the bell sinks. The receptacle is fastened in the upper part of the bell in any suitable manner, as by chains 12, which may be looped or hooked to handles 14 on the under side of the container.

When it is desired to charge the generator, after opening the air-cock 15 and removing the plug 16 from the air-vent 17, the bell is lifted from the well by means of the handles 19, and then inverted to give ready access to the carbide-receptacle. After unfastening the chains 12 the receptacle 8 is lifted from the bell 2 by the handles 14, and after

being filled with carbide it is placed in the bell and secured by the chains. The bell is then lowered into the well. The air vent 17 is closed by the plug 16, but the air-cock 15 60 is left open until the air is driven out by the gas and is then closed.

When the bell is lowered into the well it descends until the lower part of the perforated conical bottom of the receptacle 8 65 is submerged but is quickly lifted by the pressure of the gas which is immediately generated. As the carbide is gradually consumed the bell sinks lower and lower, permitting the water to rise higher in the receptacle until all the gas has been liberated 70 by the action of the water upon the carbide.

For the purpose of overcoming the fluctuations in gas pressure at the burners we provide a pressure regulator which maintains a substantially constant pressure in the gas main 21. The pressure regulator comprises an outer inverted container 23 which is loosely supported upon a shelf 24, fastened to the pipe 25, to permit the water to 80 rise in the lower part of the container 23 sufficiently to form a water seal. A cylindrical pocket or recess 27 in the carbide holder 8, permits the latter to move over the regulator as it rises or falls. The gas-regulator 85 bell 30 can rise and fall within the container 23, the pressure required to lift it being accurately adjusted by the weights 31 until the pressure is attained which it is desired to maintain in the gas main. The U-shape inlet pipe 34, by which the gas enters the bell 30, is rigidly fastened by straps 35 to the inner wall of the bell and is moved up and down therewith, being guided through openings 36, 37 in the plate 24. An extension 34' 95 depends from the bend in the pipe 34 and forms a closed trap for any moisture carried by the gas. When the gas in the pressure regulator bell 30 is reduced below normal pressure the bell descends to the position 100 shown in Fig. 1, and the gas within the main generating bell 2, flows through the U-shaped inlet pipe 34 until the gas pressure is sufficient to lift the weights 31 and raise the bell to the upper position indicated in dotted lines in Fig. 4, thereby forcing the inlet opening of the pipe 34 against the closure-pad 38, carried by the bracket 39.

The gas passes from the pressure bell 30 into the gas-main 21, through the U-shape 110 outlet pipe 25, which is provided with a closed trap extension 25^a at the bottom and

at the top with a bend 25^b and closed trap extension 25^c to receive any moisture or condensation carried over by the gas and prevent it from entering the gas main.

- 5 To further prevent moisture or foreign matter from entering the gas outlet 25, we attach a short length of pipe 25' of larger diameter to the upper end of the outlet pipe 25, and insert a tubular holder 40 carrying a number of sieves or filters 41. If at any time there is an accumulation of water in the traps 25^a, 25^c and 34' the main and pressure bells are removed after which the filter tube 40 may be lifted out and the pump 10 42, inserted, for example, into the pipe 25 until its lower end extends into the water-trap 25^a. Upon lifting the pump plunger 43 the water will be drawn into the pump cylinder.
- 15 20 The operation of our apparatus will be understood from the foregoing detailed description. The gas will be generated in the main bell 2, as long as there remains any uncombined carbid in the container, 8, the bell 2 gradually descending and immersing the carbid container deeper in the water in the well 1, as the carbid is exhausted.

The pressure regulator bell 30 will continually rise and fall with the fluctuations in the gas main in accordance with the consumption at the burners, causing the open end of the inlet pipe 34 to engage or move away from the closure pad 38 in a manner to keep the gas pressure in the bell 30 practically constant. The result of this automatic regulation of the gas pressure in the gas mains is to prevent any flickering at the burners and to maintain a steady light.

We have described in detail the particular construction illustrated in the accompanying drawings for the purpose of clearly disclosing an embodiment of our invention but it will be evident to engineers that various changes and modifications can be made 40 45 therein within the scope of our claims and without departing from our invention.

We claim—

1. In an acetylene gas generator, wherein 50 a main gas bell carrying a perforated carbid receptacle is movable vertically within a well or tank adapted to contain a supply of water and dipping into the water, and an outlet main or pipe extends into said bell the combination with said outlet main of a pressure regulator inclosing the mouth of said

5 pipe within said main bell and comprising a vertically movable regulator bell, a support therefor below the level of the water in the main bell, an inlet pipe carried by said regulator bell and connecting the interior 60 thereof with that of the main bell, and a closure adapted to close the outer end of said inlet pipe when the regulator bell is lifted by the contained gas pressure.

2. In an acetylene gas generator, having 65 a well or tank adapted to contain a supply of water, a main gas bell carrying a perforated carbid receptacle movable vertically within said tank and dipping into the water, and an outlet main or pipe extending into 70 said bell, the combination with said outlet main of a pressure regulator surrounding the mouth of said pipe within said main bell and automatically controlling the gas pressure within said main, said regulator comprising 75 an outer inverted casing or shell having a closed upper end, a regulator bell vertically movable within said casing and weighted to maintain a predetermined internal pressure, a support or platform 80 upon which said casing and said regulator bell are held, an inlet tube connecting the main gas bell with the interior of said regulator bell and secured to the latter to move therewith, and a stop or closure carried by 85 said casing and adapted to close the outer end of said inlet tube when the regulator bell is in its uppermost position.

3. In an acetylene gas generator, a well 90 or tank adapted to contain a supply of water, a main gas bell carrying a perforated carbid receptacle movable vertically within said tank and dipping into the water, an outlet main or pipe extending into said bell and having a water-drip portion extending 95 below the well of said tank to receive any water or moisture condensation in the pipe, and a pressure regulator comprising a small auxiliary bell vertically movable within the main gas bell, said auxiliary bell surrounding the mouth of the outlet pipe and automatically controlling the gas pressure in 100 said gas main.

In testimony whereof we affix our signatures in presence of two witnesses.

CLAYTON T. COOK.
CHARLES B. COOK.
